SILENCER FOR FLUSHING CISTERNS

Herbert J. Moffatt, 16 Cary St., Manly,
New South Wales, Australia

Filed May 14, 1969, Ser. No. 17,152

Claims priority, application Australia Dec. 13, 1968

Term of patent 14 years

Int. Cl. D23—02

U.S. Cl. D23—39

FIG. 2.

FIG. 3.

FIG. 4.

FIG. 5.

FIG. 1.

FIG. 6

FIG. 7.

FIG. 1 is an end view of the silencer for flushing cisterns embodying my new design;

FIG. 2 is a side view thereof;

FIG. 3 is a top plan view thereof;

FIG. 4 is a sectional view taken on line 4—4 of FIG. 3;

FIG. 5 is a bottom plan view thereof;

FIG. 6 is an end view opposite that shown in FIG. 1;

FIG. 7 is a sectional view taken on line 7—7 of FIG. 3.

I claim:

The ornamental design for a silencer for flushing cisterns, as shown.
